UNITED STATES PATENT OFFICE

KNUTE E. CARLSON, OF CAMPBELL, MASSACHUSETTS

APPARATUS FOR MOISTENING SHOES

Application filed December 13, 1929. Serial No. 413,784.

This invention relates to apparatus for moistening shoes during their manufacture.

One object of the invention is to provide novel apparatus of the character specified with which the heel portions of a shoe may be conveniently and efficiently moistened during the manufacture of the shoe to facilitate the production of smooth, neat and nice appearing counters or heel portions of the

10 shoes.

A further object of the invention is to provide a novel apparatus of the character specified which has provision for simultaneously moistening both the toe and heel portions of 15 one or more shoes so that both such portions may be made smooth, free from wrinkles, and of a highly attractive appearance, in an efficient, simple and practical manner.

With these objects in view, and such others 20 as may hereinafter appear, the invention consists in the apparatus for moistening shoes and in the structures, arrangements and combinations of parts hereinafter described and particularly defined in the claims 25 at the end of this specification.

In the drawings illustrating the preferred embodiment of the invention:-

Fig. 1 is a plan view of the apparatus embodying the present invention;

Fig. 2 a front side elevation of the apparatus shown in Fig. 1, and

Fig. 3 an enlarged cross-section taken on the line 3—3, Fig. 1.

The present apparatus is an improvement 35 on the apparatus for moistening toe pieces of shoes forming the subject-matter of the patent to Carlson, et al. No. 1,130,374 March 2, 1915. In such prior apparatus, provision was made for operatively supporting 40 the shoe with the toe portion exposed to steam to the end that the toe portion might be moistened and rendered workable and in a condition in which it might be effectively applied in a smooth condition to the toe of the 45 last in a minimum time and with minimum labor.

The present invention contemplates an improvement upon the apparatus forming the subject-matter of said patent, and particularly in that provision is made for moisten-

ing the heel portions of the shoe by exposing the same to steam to thereby render the heel portions and particularly the counters more workable, thus facilitating the production of shoes having smooth, neat and attractive 55 counters and heel portions. The present apparatus enables more inexpensive leathers to be employed in the production of such parts of the shoe than has heretofore been possible and at the same time enables as neat and attractive heel and counter portions to be produced as with the more expensive and more easily worked leathers. In its preferred form the invention contemplates a shoe-moistening apparatus which has provision 60 for effecting the simultaneous moistening of both the heel and toe portions of the shoe.

Referring to the drawings, in the illustrated apparatus 10 represents a steam chamber provided with an opening 12 in the front wall thereof through which the toe portion or portions of one or more shoes supported upon supporting members 20 are extended into the steam chamber to be subjected to the moistening effect of steam. The steam chamber 10 may and preferably will be constructed in detail as shown in the Carlson Patent No. 1,130,374 to which reference is made for details of construction not herein illustrated. The apparatus is also provided with a steam chamber 15 having curved portions 16 of the general shape of the heel of a shoe and such curved portions 16 are provided with a series of small holes or perforations 18 through which steam may pass from the chamber 15 and be thereby directed against the heel or counter portions of the shoe. The shoe is operatively supported during the moistening operation in the position illustrated in dotted lines in Figs. 1, 2 and 3 upon a support comprising a wire 20 bent into the shape illustrated in Fig. 1 and having its ends pivotally supported in lugs, one of which is shown at 22 in Fig. 1. The wire 20 is operatively supported in a substantially horizontal position by strut members 24, the ends of which are removably received in brackets 26 attached to the front wall of the steam chamber 10. The support 20 is arranged to position the toe and heel 100

portions of the shoe in the proper relation to both steam chambers 10 and 15, so that the described moistening operations upon both toe and heel portions may be simultaneously effected, thus enabling these operations to be performed in a minimum time and at a minimum expense.

In the illustrated apparatus provision is made for operatively supporting two shoes each in a position in which the toe portion of the shoe extends through the opening 12 in the front wall of the steam chamber 10 and the heel portion of the shoe is positioned within the curved section 16 of the steam chamber 15 to thereby enable both the toe and heel portions of both shoes to be simultaneously moistened by exposure to steam.

Steam may and preferably will be supplied to the apparatus from any convenient source as by the steam line 30 and through the inlet pipe 32 leading to the steam chamber 10 near the bottom thereof. The supply of steam to the chamber 10 may and preferably will be controlled by a valve 34. As herein shown, steam is supplied to the steam chamber 15 through the pipes 36 leading from the pipe 30 and through the pipe 37 leading into the steam chamber 15 near the bottom thereof, as illustrated in Figs. 1 and 3. The supply of steam to the chamber 15 may and preferably will be controlled by a valve 38 in the steam line 37.

The condensate from the steam chamber 10 is conducted away through a drain pipe 40 and the other details of construction of the chamber 10 may and preferably will comprise those illustrated in the aforesaid Carlson Patent No. 1,130,374 to which reference may be had for further description thereof.

40 The excess condensate within the steam chamber 15 above the level of the overflow pipe 44 is returned through the pipe 44 and pipe line 45 into the general outlet pipe 40 leading from the steam chamber 10.

45 The steam chamber 15 may and preferably will be provided with a perforated diaphragm 48 positioned as illustrated in Fig. 3 to provide a baffle and prevent the entrainment of water with the steam into the upper section 50 of the steam chamber and to thereby reduce to a minimum the excessive escape of water through the spray holes 18 so that the moistening action may be effected by steam alone and the most desirable effects in softening and rendering the counter or heel portions workable may be secured.

55 A gutter member 50 is provided around the curved portions 16 of the chamber 15 in order to catch condensing steam, and the gutter member is arranged to drain back into the steam chamber through one or more openings 51. The gutter serves to prevent the dripping of condensed steam down over the counters.

Both the steam chambers 10 and 15 are operatively supported in a metal supporting

framework indicated generally at 53 to form a unitary apparatus which may be transported and set up in a simple and convenient manner.

As used throughout the specification, the word "shoe" is intended to include both boots and shoes.

While the preferred embodiment of the invention has been herein illustrated and described, it will be understood that the invention may be embodied in other forms within the scope of the following claims.

Having thus described the invention what is claimed is:

1. In apparatus of the character described, in combination, a support for a shoe, a steam chamber provided with a curved portion, an inlet for admitting steam to the steam chamber, an outlet for removing the water of condensation from the steam chamber, a plurality of small perforations in said curved portion through which the steam may pass to be directed against the shoe heel, and a perforated partition in the chamber located below said perforations for preventing the entrainment of water with the steam.

2. In apparatus of the character described, in combination, a support for a shoe, a steam chamber provided with a curved portion, an inlet for admitting steam to the steam chamber, an outlet for removing the water of condensation from the steam chamber, perforations in said curved portion through which the steam may pass to be directed against the shoe heel, a perforated partition in the chamber located below said perforations, and a gutter member upon the outer wall of said curved portion.

3. In apparatus of the character described, in combination, a steam chamber provided with a curved portion adapted to fit around the heel of a shoe, means for admitting steam to the chamber, perforations in the curved portion for directing steam against the shoe heel, a gutter member upon the outer wall of the curved portion, and a support for operatively positioning a shoe with respect to the steam chamber.

In testimony whereof, I have signed my name to this specification.

KNUTE E. CARLSON.
